UNITED STATES PATENT OFFICE.

HENRY ORVILLE LOTHROP, OF BOSTON, MASSACHUSETTS.

MACHINE FOR SHAPING FERRULES.

SPECIFICATION forming part of Letters Patent No. 290,250, dated December 18, 1883.

Application filed August 1, 1883. (No model.)

To all whom it may concern:

Be it known that I, HENRY ORVILLE LOTHROP, of Boston, in the county of Suffolk, of the Commonwealth of Massachusetts, have 5 invented a new and useful Improvement in Machinery for Shaping Ferrules; and I do hereby declare the same to be described in the following specification and represented in the accompanying drawings, of which—

10 Figure 1 is a front elevation, and Fig. 2 a vertical section, of a machine embodying my invention, the nature of which is defined in the claims hereinafter presented. Fig. 3 is the end view of a cylindrical ferrule, while 15 Fig. 4 is an end view of it as it appears after having been stretched in one direction and contracted in another by the said machine.

Tool or brush handle ferrules are usually constructed as short cylindrical tubes, made 20 either of sheet metal or of wire, such wire, for being converted into a tube, being bent spirally about a mandrel or former, the coils of the spiral being in the meantime laid closely together and connected by solder.

25 The purpose of the machine hereinafter described is to expand or stretch laterally such a short tube or ferrule, in order to impart to it an elliptical, oval or pyramidal, or other desired form in its transverse section, such 30 form depending on those given to the devices which, extended within the tube, operate to stretch it one way and contract it another laterally of it.

In the drawings, A and B represent what I 35 term the two "stretchers," each being a stud whose transverse section is a circular, elliptical, oval, or polygonal segment. In Fig. 1 each of such studs is represented as semicircular in end view, each, therefore, being a semi-40 cylinder whose transverse section is a semi-circle. Each of such stretchers projects from one of two plates, a and b, in manner as shown. The upper of such plates is bolted to a stationary bar, c, the lower plate being secured 45 to a carrier, d, arranged beneath the bar c, and adapted to slide vertically on and between stationary guides e e. From the said carrier a stiff rod, f, extends downward, and is jointed to the shorter arm of a lever, g. This lever is 50 to be supposed to have a heavy weight on its longer arm. The said rod, lever, and weight

are to effect upward movements of the said carrier and its stretcher.

Into a projection, h, extending from the carrier d, a vertical rod, i, is screwed, such rod 55 extending down through a stationary guide, k, and being at top furnished with a hand-wheel, l, whose periphery is milled or provided with a series of notches or teeth extending around it, to engage with a spring catch or pawl, m, 60 fixed to a post or standard, n.

Over the upper end of the rod i there is a cam, o, which is fixed on a rotary shaft, p, supported in boxes q q, projecting from the post n. A gear, r, engaging with a pinion, s, 65 fixed on a driving-shaft, t, revolves loosely on the shaft p, and is connected thereto so as to revolve the shaft by means of a clutch, u, properly applied to shaft, and provided with an elastic shipper, v. A spiral spring, w, 70 when hooked on the shipper, serves to hold the parts of the clutch in engagement. By unhooking the spring from the shipper v, the elasticity of the latter will move it so as to cause the gear r to be unclutched from the 75 shaft p.

There is on the shaft p a notched cam, x, formed as shown in Figs. 1 and 2. This cam operates with a spring, y, which at its upper part is secured to the post n, such spring being 80 furnished with a tooth, z, to bear against the periphery of the cam x. At its lower end the spring y is secured to a plate, C, which I term the "ferrule-discharger," such plate being arranged between the bar e and carrier d, and 85 extended laterally in opposite directions beyond the two stretchers, in manner as shown in Fig. 1. Furthermore, flanking the two stretchers, or arranged as shown in Fig. 1, are two adjustable gages, D E, provided with adjusting-screws F F. These gages are to slide horizontally toward or away from the stretchers, their distances from such stretchers being determined by the said screws. The gages are to hold the ferrule in its proper position on 90 the upper stretcher, A, preparatory to the lower stretcher being depressed, in order to expand the ferrule in a vertical direction and contract it horizontally.

In using this machine, the cylindrical ferrule 100 is to be placed on the upper stretcher so as to hang thereon, both stretchers being extended

within such ferrule. The shaft *p*, being in revolution in the direction denoted by the arrow in Fig. 2, will revolve the cam *o* and cause it to depress the rod *i*, whereby the carrier *d* and the lower stretcher will be forced downward. In descending, the lower stretcher will stretch and contract the ferrule in manner as described, so as with the upper stretcher to reduce it to the required form in its transverse section. On the crank *x*, revolving far enough for the tooth of the spring *y* to enter the notch of such cam, the discharger *C* will be shot forward by the spring, and will force the bent ferrule off the stretcher *A*. The extent of downward movement of the carrier can be varied, as occasion may require, by turning the screw-rod *i*, to either increase or diminish

the extent of projection of such rod above the carrier.

I claim—

1. The combination of the stationary stretcher *A* with the movable stretcher *B* and the discharger *C*, having mechanisms for operating them, substantially as set forth. 20
2. The combination of the adjustable gages *D* and *E* with the stationary stretcher *A*, and with the movable stretcher *B* and the discharger *C*, provided with mechanisms for operating them, substantially as set forth. 25

HENRY ORVILLE LOTHROP.
